UNITED STATES PATENT OFFICE.

JOHN WICKS, OF CHICAGO, ILLINOIS, ASSIGNOR TO AUTOMATIC ELECTRIC COMPANY, OF CHICAGO, ILLINOIS, A CORPORATION OF ILLINOIS.

MULTIOFFICE TELEPHONE SYSTEM.

Application filed November 15, 1919. Serial No. 338,380.

To all whom it may concern:

Be it known that I, JOHN WICKS, a citizen of the United States of America, and a resident of Chicago, county of Cook, and State of Illinois, have invented certain new and useful Improvements in Multioffice Telephone Systems, of which the following is a specification.

My invention relates in general to multi-office telephone systems and is particularly well adapted for use in such systems as are going thru a period of transition from manual operation to automatic operation, there being some offices or exchanges of the system which have full automatic equipment while the other offices still have the manual equipment. However, certain features of the invention are of value in ordinary manual multi-office systems not including automatic equipment, while certain other features are applicable to the so called semi-automatic systems, although it is conceived that the invention broadly will find its chief use under the circumstances first stated.

In changing a large manual multi-office system over to automatic equipment it is considered the best practice to do so gradually, one office at a time, rather than to attempt to change all offices at once. In fact the latter method would in practice be very difficult if not impossible to accomplish successfully. It follows therefore that after the changeover is started and until it is completed certain of the offices will have automatic equipment while the others still have the operators. The problem then is presented of providing suitable trunking facilities between manual and automatic exchanges.

This invention is not concerned especially with the trunking from the automatic exchanges to the manual, there being suitable means available already for handling such traffic, but its object is to provide a new and better arrangement of trunking from the manual offices to the automatic offices, and incidentally, in order to permit a uniform routine of operation on the part of the operators, to provide an improved trunking arrangement between the manual offices themselves.

Other objects consist in providing improved circuit details and mechanism which with the improved trunking arrangements above mentioned will be fully described here-

inafter, reference being had to the accompanying drawings.

Referring to the drawings, Fig. 1 is a schematic diagram showing the trunking arrangement between two manual offices, while Figs. 3 and 4 are circuit diagrams showing the apparatus required to establish a complete connection between subscribers in different manual offices which are interconnected by a system of trunks such as is shown in Fig. 1. The left hand portion of Fig. 1 up to the dotted line and Fig. 2 shows a schematic diagram of the trunking arrangement used for handling calls from a manual office to an automatic office. The remaining sheets of drawings, Figs. 5 to 9, inclusive, taken in connection with Fig. 3, show circuits of the apparatus used in completing a connection from a subscriber in the manual office to a subscriber in an automatic office, according to the second trunking arrangement, or at least so much of the circuits is shown as is necessary to enable the invention to be understood.

The general system of trunking from a manual office to a second manual office will first be briefly explained. Referring to Fig. 1, jacks J^1 to J^4 are four of a plurality of outgoing trunk jacks at the A board of a manual office which will hereinafter be termed the No. 1 office or exchange. These jacks are preferably multiplied in a certain number of other positions as indicated; and are directly connected to primary rotary line switches P^1 to P^4 , respectively. These line switches may be of 25 line capacity and as each of the switches shown has access to a different plurality of trunks there will be 100 trunks extending to the second or No. 2 manual office. Each of these trunks terminates at the No. 2 office in a secondary rotary line switch, and four of these switches are indicated by reference characters S^1 to S^4 . The number of cord circuits at the B board in the No. 2 exchange for handling calls from the No. 1 exchange should be somewhat in excess of the number of trunks, allowing for repairs, etc., and we may assume that 120 cord circuits are provided which are divided into two groups of 60 cord circuits for each of two positions. Four cord circuits C^1 to C^4 are shown, which are located at the 1st position and the other four, C^5 to C^8 , are at the 2nd position. These cord circuits are accessible to the sec-

ondary switches such as S' , S^2 , etc., and may be multiplied in the banks of these switches as desired, care being taken however to give each switch access to cord circuits in both 5 positions. In the present case the switches S' , S^2 , etc., may be 30 point switches and may be divided into 4 groups having access to 15 cord circuits at each position. Of course the capacity of the switches is immaterial, and they may be of any desired capacity. It has been stated above that the jacks J' , J^2 , etc., are multiplied in other positions. In the case of a large A board as is herein contemplated it will usually be best to divide 15 the board into two or more sections and multiple the first group of outgoing trunk jacks only in the first section which may arbitrarily have 10 or more positions, the term section as here used not referring 20 to the standard 3 position section. An independent multiple will be provided for each of the other sections, one such being represented by the jacks J^5 , J^6 , etc., which are connected to primary switches P' , P^2 , etc. 25 These switches have access to the same groups of trunks as do the switches P' , P^2 , etc. Thus it will be seen that an excessively large outgoing trunk multiple at the A board will never be required. 30 It will be understood that the foregoing explanation considers only the trunking between the No. 1 office and the No. 2 office. There will be a similar system of trunks extending from the No. 1 office to each of the 35 other manual offices, as is the usual practice. Likewise there will be a system of trunks from the No. 1 office to each of the automatic offices in the system and the trunking to one of these offices, which will be termed the 40 No. 3 office, will now be explained.

The outgoing trunk multiples at the A board of the No. 1 office are identical so far as general arrangement and trunking is concerned, whether they extend to manual offices or to automatic offices. In view of 45 this fact, it is not considered necessary to show the outgoing trunk multiple to the No. 3 office because for purposes of illustration Fig. 2 may be joined to Fig. 1 at the dotted line so that the four trunk lines which extend from the first contacts of primary switches P' to P^4 will continue into Fig. 2 and terminate in secondary switches S^5 to S^8 , respectively. These latter switches may 50 be of 30 trunk capacity and are divided into four groups, there being shown one switch of each group. There will be therefore a total of 120 trunks in the layout as shown, and each trunk extends by way of a relay equipment such as M' to a first selector switch such as H' . It will be seen that there 55 are two B operators positions, each being arranged to handle 60 trunks. Considering the first position, the 60 trunks are divided 60 into three groups of 20 trunks each and call-

ing devices or operator's senders N' , N^2 , and N^3 are provided which control the establishment of connections over the 3 groups of trunks, respectively. All three senders are in turn controlled by the operator thru the medium of a set of keys indicated by references character K' . The arrangement at the second position is the same. In multiplying the trunks in the banks of the switches S' , S^2 , etc., the arrangement should be such that there are a certain number of trunks, 5 in this case, extending from the banks of each of the four groups of switches to each of the 6 operator's senders; or in other words, the 20 trunks controlled by each sender should be divided into as many groups as there are groups of secondary switches and each group of trunks should then be multiplied in the banks of a different group of switches. 70 75 80 85

The foregoing will be sufficient it is believed to make clear the general layout of the system. The method of operation and the circuits will be described fully in the detailed specification which is to follow. In order to reduce the amount of descriptive matter in the specification, the apparatus used, such as the automatic substations, the primary and secondary line switches, the selector switches and other switches comprising the automatic exchange, and the operator's senders and key equipment, will not be described in detail, but instead reference is made to the following patents: British patent to Dicker #29,654 of 1910, U. S. patent to Land #1,146,177, U. S. patent to Lamb #1,193,160, U. S. patent to Keith Erickson and Erickson #815,321, U. S. patent to Keith Erickson and Erickson #815,176, U. S. patent to Blessing #1,209,253, 90 95 U. S. patent to Powell #1,308,553. 100 105 110

Having given a general description of the trunking system as a whole, I will now describe the operation thereof more in detail, it being assumed first, referring to Figs. 3 and 4, that the subscriber at substation A whose line is connected to the No. 1 office desires to obtain connection with the subscriber at substation A' whose line is connected to the No. 2 office. When the subscriber at substation A removes his receiver from the hook a circuit is completed which extends from ground thru the cut off relay 2, over the line and thru substation A, and returning on the other side of the line thru the line relay 3 to battery. The line relay 3 is energized upon the closure of the above circuit and completes a circuit for the line lamp L; but relay 3 being of high resistance, the cut off relay 2 is prevented from energizing at this time. When the operator observes the lighted condition of the lamp L she will respond by inserting the answering plug of an idle cord circuit, for example the cord circuit C, in the jack J, at the same 115 120 125 130

- time throwing her listening key K. Upon the insertion of the plug in the jack a circuit is completed over the tip of the plug which connects the cut off relay 2 and the 5 relay 4 of the cord circuit in series. Both relays are energized, relay 4 closing a pair of contacts in the circuit of the supervisory lamp L', and the cut off relay switching the ring side of the line from connection with the line relay 3 into connection with the 10 sleeve of jack J, thereby placing a potential upon the sleeve of jack J and its multiples (not shown) whereby the line of substation A is made busy at other positions. 15 At the same time that relay 4 is energized as described relay 5 is also energized over a circuit which extends from ground thru cut off relay 2, thru substation A, and back over the ring side of the line thru relay 5 to the 20 battery. Relay 5 opens a pair of contacts in the circuit of the supervisory lamp L'. 85

When the subscriber at substation A hears the operator on the line, he will repeat the number of the subscriber with 25 whom he wishes to be connected, as is the well known practice. Upon learning that the desired subscriber is in the No. 2 office, the operator will test the out going trunk multiple of the No. 2 office with the tip of 30 her plug in the usual manner in order to locate an idle jack. Assuming that the jack J' is found to be idle the operator will insert the calling plug, whereupon a circuit is completed for the relay 6 as follows: 35 Ground at G', resting contact of armature 18 and the said armature, ring spring of jack J', ring of plug, and the winding of relay 6 to battery. Upon energizing, relay 6 opens a pair of contacts in the circuit of the lamp L², and also completes an initial 40 energizing circuit for relay 7 which extends as follows: Ground at G², winding of relay 11, tip spring of jack J', tip of plug, contacts of relay 6, and the winding of relay 7 to battery. Upon energizing relay 7 closes its own circuit independent of relay 6 and also prepares a circuit for the supervisory lamp L². 105

The energization of relay 11, which is the 50 line relay of the primary line switch P', over the circuit described above, causes the initiation of the trunk selecting movement of this switch whereby an idle trunk line extended to the No. 2 office is selected. 55 Upon attracting its armature 14, relay 11 completes a circuit including the winding of the switching relay 12 and the stepping magnet 13 in series. At the same time this circuit is closed the test wiper 22 is connected by way of armature 17 and its resting contact and armature 15 and its working contact to a point midway between relay 12 and the said stepping magnet. The 60 operation now depends upon whether the 65 test contact with which the test wiper 22 is

in engagement is or is not busy. If this test contact is busy there will be a ground potential upon it and the switching relay 12 will be short circuited in an obvious manner. At the same time the stepping 70 magnet, being supplied with direct ground via the test wiper and busy test contact, will begin operating to rotate the wipers 21, 22, and 23 step by step in search of an idle trunk extending to the No. 2 exchange. 75 This is the usual operation of a rotary switch of this type in the case where its operation is initiated when its wipers are standing upon the contacts of a trunk line which is busy. However, in the present 80 case we may assume that when the operation of the line switch P' is initiated its wipers are standing upon the contacts which are terminals of the trunk conductors 25 and 27 as shown in the drawing, and we may assume furthermore that this trunk line is 85 idle at the time. Under these circumstances, when the circuit of the switching relay 12 is closed thru the stepping magnet 13 the 90 said relay 12 will not be short circuited and the stepping magnet will not operate owing to the high resistance of relay 12. The relay 12 is energized with the following results: At its armature 18 ground G' is 95 disconnected from the ring side of the line circuit thereby causing relay 6 in the cord circuit to deenergize and close the circuit of the calling supervisory lamp L². At armature 17 ground G² is connected to the 100 test wiper 22 thereby completing a circuit over the conductor 26 to the relay 28, which is one of a series of chain relays which are provided, one for each trunk, for the purpose of connecting battery to the common conductor 29 whenever all the outgoing 105 trunks in the group become busy. The sleeves of the jack are all normally connected to this common conductor 29 by way of contact springs, such as the contact spring 16, of the associated primary line switches, 110 so that in case all the trunks are busy the entire outgoing multiple will test busy to the operator. Finally, at the working contacts of armatures 19 and 18 the two sides of the line circuit are extended by way of 115 wipers 21 and 23, the bank contacts upon which these wipers are now standing, line conductors 25 and 27, and the resting contacts of armatures 33 and 34 of relay 30 to the winding of the line relay 31 of the 120 secondary line switch S'. 125

It will be seen that the line relay 31 is thereby bridged across the line and will be energized by current flow from ground at G² thru the line relay 11 of the primary line switch P', over the upper line conductor, thru the said line relay 31, over the lower line conductor and thru the winding of relay 6 of the cord circuit C to battery. Relay 31 is of high resistance and does not 130

permit enough current to flow to cause the operation of relay 6, but energizes immediately itself and closes a circuit for the relay 32. Upon the operation of relay 32 circuits 5 are closed which correspond to similar circuits whose operation has been described in connection with the primary line switch P', whereby the secondary switch S' is caused to select and establish connection with an 10 idle cord circuit. These operations having already been described will not be considered again in detail, but it will be sufficient to say, assuming that the cord circuit C' is idle, that the switching relay 30 15 is energized, whereby the line conductors are extended by way of armatures 33 and 34 and their working contacts, wipers 40 and 42, the bank contacts with which these wipers are in engagement, and the upper 20 and lower windings of the repeating coil R to the windings of the relay 60. Relay 60, or at least its left hand winding, is of high resistance and this relay is now energized over a circuit similar to that by which the 25 line relay 31 of the secondary switch S' was energized, relay 6 at the cord circuit C' remaining inoperative as before. Upon energizing, relay 60 completes a circuit which extends as follows: Ground G⁴, working contact of armature 82 and the said armature, and the winding of relay 43 to battery. Upon energizing in its turn, relay 43 completes a holding circuit for the switching relay 30 of secondary switch S' which may 30 be traced over the following path: Ground at G⁵, working contact of armature 49 and the said armature, resting contact of armature 83 and the said armature, test contact upon which the test wiper 41 is now resting and 35 the said test wiper, armature 35 and its working contact, winding of the switching relay 30 and the winding of the stepping magnet 36 to battery.

It is understood that this holding circuit is 40 established before the slow acting relay 32 has had time to deenergize. A branch of the holding circuit just traced extends by way of the resting contact of armature 52 and the said armature to the common conductor 59, 45 thereby grounding this conductor. Conductor 59 is multiplied to contact springs corresponding to armature 52 in all the other cord circuits at the position, and when grounded therefore has the function of rendering all the cord circuits busy.

As a further result of the energization of 50 relay 43 ground G⁶ is connected by means of armature 50 to the windings of relays 45 and 64, both of which relays are energized. Relay 45 at its armatures 57 and 58 connects the operator's head set across the trunk circuit whereby she is put in communication with the operator at the No. 1 exchange. Relay 64 at its armature 70 closes a circuit for the 55 lamp L² which extends as follows: Ground

at G⁷, interrupter I, normally closed contacts controlled by armature 73 of relay 63, armature 74 and its resting contact, working contact of armature 70 and the said armature, and the lamp L² to battery.

Connection having been established between the two operators, the A operator will now repeat the desired number to the B operator who, being advised which of her cord circuits is to be used by the flashing of the lamp L³, will test the desired line and upon finding it idle will insert the plug of cord circuit C' in multiple jack J¹⁰. Upon the insertion of the plug a circuit is completed for the relay 62 as follows: Ground at G⁸, 70 winding of relay 62, resting contact of armature 78 and the said armature, resting contact of armature 79 and the said armature, ring of plug, ring spring of jack J¹⁰, normally closed contacts of the cut off relay 2', 75 and the winding of the line relay 3' to battery. Upon energizing, relay 62 closes the following circuit: Ground at G⁹, working contact of armature 75 and the said armature, winding of relay 67, and the resistance 80 r to battery. Relay 67 is energized and at its armature 76 completes an energizing circuit for relay 66 which relay at its armature 78 opens the circuit of relay 62. Upon deenergizing, relay 62 breaks the original energizing circuit of relay 67, but this relay is 85 not deenergized, remaining locked up over the following path: Ground at G¹¹, winding of the cut off relay, tip spring of jack J¹⁰, tip 90 of plug, armature 80 and its working contact, the winding of relay 67, and the resistance r to battery. As a further result of the energization of relay 66 the upper and lower line conductors are closed at the working contacts of armatures 77 and 78, and at 95 armature 74 the circuit of the lamp L³ is broken. In addition, at the working contact of armature 74 a circuit is established for relay 63 as follows: Ground at G⁷, interrupter 100 I (the first time this interrupter closes the circuit), normally closed contacts controlled by armature 73 of relay 63, armature 74 and its working contact, armature 69 and its working contact, and the winding of relay 63 to battery. Upon energizing, relay 63 105 locks itself independent of relay 64 at its armature 72, and by means of armature 73 substitutes direct ground for the interrupted ground G⁷. A branch of the circuit by 110 which relay 63 was energized may be traced from the junction point 84 by way of armature 56 and its working contact, normally closed contacts controlled by armature 51, and the winding of relay 44 to battery. Upon energizing relay 44 completes a locking circuit for itself at its armature 51; 115 breaks the circuit of relay 45 at its armature 53, whereby the operator's head set is disconnected from the trunk; and at armature 52 removes ground G⁵ from the com- 120

mon conductor 59, whereby the remaining cord circuits at the position are rendered accessible to incoming calls.

Returning now to the relay 67, which is the ringing relay, when this relay was energized a circuit was established by means of armature 79 over which ringing current from the ringing current generator Gen is projected out over the called line in the usual manner to signal the called subscriber. Relay 68 is included in this circuit and is so adjusted that it does not respond to the ringing current as long as the receiver at the called station is on the hook. When the 15 called subscriber answers, however, relay 68 is operated, either by ringing current from the generator Gen or by direct current from the battery associated therewith, and short-circuits the winding of the ringing relay 67. 20 Relay 67 is accordingly deenergized and in addition to breaking its own locking circuit at armature 80 this relay opens the original energizing circuit of relay 66, which is hereafter maintained energized over the tip side of the line to ground G^{11} thru the winding of the cut off relay 2'. As a further result of its deenergization, relay 67 disconnects the ringing current generator and closes the 25 ring side of the line at armature 79. The receiver being off the hook at the called station a circuit is now established which extends from ground G^{11} thru the winding of the cut-off relay 2', thru the substation A', and back on the other side of the line circuit to the ring side of the cord circuit whence it 30 extends thru the winding of relay 61 to battery. Upon energizing, relay 61 connects the impedance coil 65 to the tip side of the talking circuit in parallel with the winding of the cut-off relay 2', and also short circuits the high resistance winding, which now permits sufficient current to flow to energize relay 6 at cord circuit C, which relay is operated to extinguish the supervisory lamp 35 L'. The A operator, who has already restored her key K, is thus notified that the call has been answered and need pay no further attention to it until one or both of the lamps L' and L² are again lighted to indicate that the conversation is finished.

The talking circuit between the two connected sub-stations is shown in heavy lines, and being furthermore of well known character, will not need to be described in detail. When the conversation is over with both subscribers will replace their receivers. Responsive to the hanging up of the receiver at substation A' the circuit of relay 5 is broken, resulting in the lighting of the supervisory lamp L'. When the receiver is replaced at substation A' relay 61 is deenergized and the high resistance winding of relay 60 is again included in the circuit of relay 6 at the cord circuit C, thereby causing this relay to deenergize and close the

circuit of supervisory lamp L². The lighting of the supervisory lamps indicates to the operator that the subscribers are truly talking and she will accordingly pull down the connection. When the calling plug is removed from jack J' the circuit of relay 11 of the primary line switch P' is broken, whereupon this relay and also the switching relay 12 are deenergized, thereby restoring the switch to normal condition ready for another call. As a further result of the removal of the plug from jack J' the circuit of relay 60 of cord circuit C' is broken and this relay therefore deenergizes to break the circuit of relay 43. Upon deenergizing, relay 43 breaks the holding circuit of the switching relay 30 of the secondary line switch S' at its armature 49, whereupon relay 30 deenergizes and the secondary line switch is restored to normal condition. Relay 43 upon deenergizing also completes a circuit for relay 46 which extends as follows: Ground at G^{12} , armature 73 and its working contact, armature 74 and its working contact, armature 56 and its resting contact, armature 47 and its resting contact, and the winding of relay 46 to battery. Relay 46 is operated and again grounds the test contact upon which test wiper 41 is resting, and multiples of this test contact (not shown), whereby the cord circuit C' is again made busy to incoming calls, the brief interval during which ground is removed from the test contact being just sufficient to provide for the restoration of the secondary switch S'. As a further result of the deenergization of relay 43, ground G^6 is disconnected from the relay 64 and this relay therefore deenergizes to close a circuit for the lamp L³, which extends as follows: Ground at G^{12} , armature 73 and its working contact, armature 74 and its working contact, resting contact of armature 70 and the said armature, and the lamp L³ to battery. The lighting of the lamp L³ gives the B operator a disconnect signal, upon perceiving which she will remove the plug from jack J¹⁰. As a result of the removal of the plug, relay 66 is deenergized, breaking at its armature 74 the circuit of the lamp L³ and also the circuit of relay 46. Relay 46 therefore deenergizes also removing ground from the multiple test contacts associated with cord circuit C', whereupon the cord circuit will be again in normal condition and ready for another call.

Having described the operation of the circuits involved in the establishment of a connection between a subscriber's line connected to the No. 1 office and a second subscriber's line connected to the No. 2 office, both of which offices have manual equipment, I will now describe the operation of the circuits involved in establishing a connection between a subscriber's line connected to the No. 1 office and a subscriber's

line connected to the No. 3 office, which as previously stated is an automatic office. Let us assume that the subscriber at substation A makes a call as before, except that now the desired line is connected to the number 3 or automatic office. In this case, then, the A operator in order to extend the connection will test the out going trunk multiple associated with the No. 3 office, and upon finding an idle jack, assumed in this case to be jack J^9 , will insert the calling plug of the cord circuit C. When the operator plugs into the jack the primary switch P^9 will be operated to extend the connection to an idle trunk line which will be assumed to be the trunk line extending to the secondary switch S^5 , Fig. 5; and immediately thereafter the secondary switch S^5 will operate to further extend the connection to an idle relay equipment. Assuming that the relay equipment M' , Fig. 5, is found to be idle and that connection is established therewith, the relay 128 will be energized over the line circuit. Relay 128 will be recognized as a relay normally having a high resistance, corresponding to the relay 60 of cord circuit C'. It follows that relay 6 of cord circuit C will remain inoperative and the supervisory lamp L^2 will continue to glow. Upon energizing, relay 128 closes the circuit of slow acting relay 129 which relay, upon attracting its armature 142, connects the right hand windings of the repeating coil R' across the trunk conductors 161 and 163. The trunk line comprising conductors 161 and 163 extends to a first selector switch (not shown) and it follows that upon the closure of the line circuit by the operation of relay 129 the line and release relays of the first selector will be energized in the usual manner thereby preparing the selector for operation responsive to interruptions subsequently produced in the line circuit in accordance with a digit in the called number. At its armature 141 relay 129 also closes a contact in the circuit of relay 111 for a purpose to be described hereinafter; and at its armature 140 connects ground G^{14} to conductor 162. As a result of this latter operation the visual signal V is actuated and also an energizing circuit is completed for the slow acting relay 130. Relay 130 upon energizing completes a holding circuit for the secondary switch S^5 as follows: Ground at G^{15} , working contact of 145 and the said armature, test contact with which test wiper 121 is in engagement and the said test wiper, armature 109 and its working contact, winding of relay 106, and the winding of the stepping magnet to battery. This circuit is established before the slow acting relay 108 has had time to deenergize, and in addition to its function of maintaining relay 106 in operated posi-

tion, it also provides ground to multiple test contacts associated with the relay equipment M' in the banks of other secondary switches for the purpose of rendering the relay equipment M' busy to other calls. It will be observed that ground G^{15} also extends by way of the working contact of 145 and the said armature, armature 148 and its resting contact, and conductor 171 to conductor 171', Fig. 7. Conductor 171' is a common conductor and has connected to it all the conductors similar to conductor 171 which are associated with the other relay equipments of the group which is controlled by the operator's sender N' . It will be seen therefore that as soon as the relay equipment M' is seized the common conductor 171' will be grounded, resulting in the grounding of all conductors such as conductor 171 which extend to other idle relay equipments in the group; and that since in all idle relay equipments the relays such as relay 130 are deenergized, the effect of grounding conductors such as conductor 171 will be to place a busy potential upon the test contacts associated with all the other idle relay equipments of the group. But this is not all. There is a common conductor such as the common conductor 171' associated with each operator's sender, the common conductor associated with the second operator's sender being indicated by reference character 271', Fig. 8. All three of these common conductors, assuming that the operator at this position has three calling devices, or senders, are connection by way of normally closed relay contacts to another common conductor 201, there being one such latter conductor to each operator's position. It follows therefore that when the relay equipment M' is seized, not only will all the other relay equipments of the group be made busy, but all the idle relay equipment of the groups associated with the other two operator's senders N^2 and N^3 will be made busy also.

Returning now to the relay 130, as a further result of its energization a circuit is completed for relay 132 which extends as follows: Ground at G^{16} , armature 214 and its resting contact, normally closed contact springs controlled by armature 225, conductor 164, armature 144 and its working contact, armature 147 and its resting contact, and the winding of relay 132 to battery. Upon energizing relay 132 connects the operator's head set across the trunk circuit by means of its armatures 150 and 152; and at armature 151 closes a circuit for relay 202, Fig. 7, which may be readily traced over conductor 169. Relay 202 accordingly energizes and at its armature 228 disconnects ground from conductor 241 for a purpose which will be explained later, and also at its armature 226 connects ground to

conductor 168, whence it extends to relay 111, Fig. 5. As before stated, the function of relay 111 and associated circuits will be explained later on. A branch of the circuit of relay 202 may be traced from junction point 242, Fig. 7, thru the windings of relays 243 and 244 in series to battery. These two relays are therefore energized and connect the conductors coming from the operator's number setting or register keys shown in Fig. 9 to the operator's sender N' . When relay 132 was energized it closed, in addition to the circuits just described, a circuit which extends from ground G^{17} by way of armature 153 and its working contact and the windings of relays 133 and 134 in series to battery. Upon energizing relay 133 establishes a locking circuit for itself and relay 134 which may be traced as follows: Ground at G^{18} , Fig. 7, normally closed contacts controlled by armature 217, armature 211 and its resting contact, normally closed contacts controlled by armature 224, common conductor 165' conductor 165, armature 154 and its working contact, and the windings of relays 133 and 134 in series to battery. At its armature 157 relay 133 connects ground to conductor 171 in order to maintain this conductor grounded after the energization of relay 131 which occurs at a further stage of the operation; and at its armatures 155 and 156 prepares circuits which need not be considered now as they remain open for the time being at other points. Relay 134, upon energizing, disconnects the trunk conductors 161 and 163 from the right hand windings of the repeating coil R' and connects them instead to conductors 166 and 167, respectively, which are connected to common conductors 166' and 167', respectively, which terminate in the normally closed interrupter or impulse transmitting springs 245 and 246 of the operator's sender N' .

The foregoing operations have all occurred automatically responsive to the seizure of the relay equipment M' by the secondary switch S^5 . The B operator having control of the sender N' will now be in communication with the A operator, her head set having been connected by the energization of relay 132, as previously stated. The A operator knows when the connection to the B operator has been completed by the cessation of the induced tone on the line (produced by signalling equipment Q while relay 107 is energized) and will now repeat the desired number. Upon learning the number the B operator depresses in rapid succession the corresponding digit keys of her key set, Fig. 9, and then depresses the key marked "start." The B operator ordinarily pays no further attention to the call after performing these operations.

In response to the actuation of the digit keys certain ones of a plurality of levers (not shown) arranged radially on the wheel 249 are set by means of an arm (also not shown) operated by the magnet 252 and controlled by the solenoids 251. In this way the required number is registered on the wheel 249. When the first digit key is depressed (and each time a key is depressed thereafter during the setting up of the number) a circuit is closed as follows: Ground at G^{20} , winding of relay 206, conductor 254, conductor 255, contacts of any depressed key, conductor individual to the depressed key, and the corresponding solenoid of the sender N' to battery. This will make it clear how the solenoids and magnet 252 are energized at proper times, the latter magnet being controlled by the relay 206 which is energized in series with one of the solenoids every time a digit key is depressed. Relay 206, at its first energization, closes a circuit for relay 207, which upon energizing, closes a locking circuit for itself at its armature 218. A circuit may now be traced from ground G^{21} by way of normally closed contacts controlled by armature 215, working contact of armature 218 and the said armature, conductor 256, and lamp L^5 to battery. Lamp L^5 is lighted when the first key is depressed and indicates that the sender is in set or partially set position but is not operating to transmit impulses.

Upon the operation of the starting key a circuit is closed for the relay 209 as follows: Ground at G^{21} , normally closed contacts controlled by armature 215, working contact of armature 218 and the said armature, conductor 257, conductor 258, contacts of starting key, conductor 259, conductor 260, and the winding of relay 209 to battery. Upon attracting its armature 214, relay 209 opens the circuit of relay 132 which relay deenergizes with important results. By retraction of armatures 150 and 152 the B operator's head set is disconnected. By the retraction of armature 151 the circuit of relays 202, 243, and 244 is broken, and these relays are deenergized, the latter two disconnecting the register keys from the sender N' , and by the retraction of armature 153 a circuit for relay 203 is closed as follows: Ground at G^{17} , armature 153 and its resting contact, working contact of armature 155 and said armature, conductor 170, common conductor 170', and the winding of relay 203 to battery. Upon energizing, relay 203 connects ground at its armature 227 to conductor 168 which it maintains grounded after relay 202 has deenergized, and at its armature 229 disconnects the common conductor 171' from the common conductor 201. By the latter operation the relay equipments of the groups controlled by calling devices N^2 and N^3 are placed in idle condition and are ready to re-

- ceive calls. This is proper, for although the sender N' has not yet performed its function (note that the relay equipments associated with N' are held busy for the present) still 5 the operator has done her part, her head set and register keys have been disconnected, and she may well busy herself by setting up another call on one of her other senders. As a final result of its deenergization, relay 10 132 closes the circuit of relay 131, ground G¹⁷ being extended by way of armature 153 and its resting contact, working contact of armature 156 and the said armature, and the winding of relay 131 to battery. Upon energizing, relay 131 establishes a locking circuit for itself at armature 148 and at armature 147 opens a contact in the circuit of relay 132 to prevent this relay from energizing again after the sender N' is restored to 15 normal.
- Returning to relay 209, an additional function of its energization is the completion at armature 212 of a circuit for the starting relay 240 of the sender N'. Upon 20 energizing the starting relay 240 closes the contact springs 272 and 273 which are locked mechanically in closed position. A circuit is thereby completed for relay 208 which upon energizing, closes a locking circuit for 25 relay 209 at its armature 215; breaks the circuit of relay 207 and of lamp L⁵ at the contacts controlled by the same armature; opens the circuit of starting relay 240 at armature 216; and finally by attracting armature 217, 30 inserts the winding of the slow acting relay 210 in the previously described locking circuit of relays 133 and 134 of the relay equipment M'. Relay 210 is accordingly energized. A branch of the circuit of relay 208 35 extends over conductor 274 to lamp L⁶ which is now lighted. A further result of the closure of springs 272 and 273 is the completion of the operating circuit of the motor 250 which now begins to rotate the wheel 249 and the impulse cam 275, the gearing for driving the latter not being shown. The 40 gears are so proportioned that the cam 275 separates the impulse springs 245 and 246 once for each lever (not shown) on the wheel 45 249 which passes the springs 276 and 277. As soon as the first displaced lever arrives at the latter springs they are closed momentarily thereby completing a circuit for slow acting relay 247. Relay 247 closes in turn 50 a circuit for slow acting magnet 248 which operates to bring a pawl into engagement with the impulse cam, thereby stopping the operation of the motor for an interval. As soon as relay 247 and magnet 248 retract 55 their armatures the motor again starts to revolve and another series of impulses is transmitted by the cam 275, the number of impulses being determined as before by the displaced lever on the wheel 249. It will be 60 clear, therefore, that the impulse sender N' 65

will operate to transmit in this manner as many series of impulses over the circuit including trunk conductors 161 and 163 as there were digit keys depressed, the number of impulses in each series being determined by the relative position of the displaced levers, which in turn depends upon which digit keys were depressed. 70

While the automatic switches which respond to the several series of impulses to 75 establish the connection are not shown, they have been described in the patents referred to, and anyway they are well understood by those familiar with the art. It will suffice to say in this connection that a plurality of serially related selector switches and a connector switch are successively operated by the successive series of impulses until the final switch which is the connector completes the connection to the desired line, 80 whereupon suitable ringing mechanism is rendered operative to signal the called subscriber. 85

After the transmission of the last series of impulses, the motor 250 continues to run 90 until the wheel 249 has made a complete rotation and returned to its starting point. Upon the return of wheel 249 to normal the springs 272 and 273 are unlocked and allowed to separate, thereby stopping the motor 250, deenergizing relay 208, and extinguishing the lamp L⁶. Upon deenergizing, relay 208 breaks the locking circuit of relay 209 at armature 215, and at armature 217 disconnects ground G¹⁸ from 95 the locking circuit of relays 133 and 134. Relay 210 which is included in this locking circuit is slow acting and hence does not retract its armature 211 until relays 233 and 234 have had time to deenergize or at least until relay 233 has opened the circuit at another point by retracting its armature 154. Relay 133, by retracting its armature 157, also removes ground from conductor 171 and, therefore from common conductor 171', with the result that the busy condition is removed from other relay equipments in the group associated with sender N'. Furthermore, at armature 155 the circuit of relay 203 is broken, which relay now 100 deenergizes to again connect common conductor 171' with common conductor 201, 105 such being the normal condition. 110

Relay 134, which was deenergized simultaneously with relay 133, has now reconnected the trunk conductors 161 and 163 with the right hand windings of the repeating coil R', these windings being conductively connected by way of the upper winding of the electro polarized relay 126, 115 Now when the called subscriber answers his telephone the direction of current flow in the trunk conductors 161 and 163 is reversed accordingly to the well known practice by a so called reversing relay in the 120 125 130

connector, with the result that the electro polarized relay 126 is operated. Relay 126 closes a circuit for self-locking relay 127 at its upper armature 135, and at armature 136 short-circuits the lower and high resistance winding of relay 128. As a result of this latter operation sufficient current is permitted to flow over the inter-office trunk coming from the No. 1 office to energize relay 6 of cord circuit C, whereupon this relay is operated to extinguish the supervisory lamp L^2 , this notifying the A operator that the call has been answered.

The desired connection has now been established and conversation may proceed. So much of the talking circuit as is shown is in heavy lines, and being of the usual character, the entire circuit will be understood without difficulty.

When the subscribers have finished talking they will replace their receivers as is customary. Upon the replacement of the receiver at substation A the supervisory lamp L^1 is lighted as previously explained. When the receiver is replaced at the called station whose line terminates in the No. 3 or automatic office the direction of current flow in trunk conductors 161 and 163 will again be reversed to normal condition, whereupon relay 126 will be caused to retract its armatures. By the retraction of armature 135 the supervisory lamp L^4 is lighted, and by the retraction of armature 136 the short-circuit is removed from the high resistance winding of relay 128. Thus current flow over the trunk from the No. 1 office is decreased sufficient to cause relay 6 of cord circuit C to deenergize and close the circuit of supervisory lamp L^2 . By the disconnect signals thus exhibited the A operator is notified that the conversation is over with and she will accordingly pull down the connection. By the removal of the plug from jack J^9 the primary switch P^9 is restored to normal, and in addition the energizing circuit of relay 128 is broken. Relay 128, upon deenergizing, breaks the circuit of relay 129, whose deenergization is followed by the deenergization of relays 130, 131, and 127; and by the extinguishing of lamp L^4 and restoration of the signal V . Relay 130 breaks the holding circuit of relay 106 of the secondary switch S^5 , which also restores; and relay 129 opens the bridge across trunk conductors 161 and 163, thereby causing the release of the automatic switches, whereupon all the apparatus in use will have been restored to normal.

An explanation will now be made of certain other features which were not covered before because it was not thought advisable to digress from the description of the routine operations. In Fig. 5 are shown three relays 111, 112, and 113, which are common to the three groups of trunks associated with

senders N' , N^2 and N^3 respectively; and a fourth relay 114, which is common to all the groups of relay equipments at all the positions which are accessible to the secondary switches. Relay 111 may be energized in two ways; either by the closing of a circuit which includes armature 141 of relay 129 of the first relay equipment M' in the group, the armature 141' which is similarly located in the second relay equipment of the group, and corresponding armatures in all the other relay equipments of the group; or by grounding conductor 168 at relay 202 or 203. It will be seen then that relay 111 will be energized when all the trunks or relay equipments in the group controlled by sender N' are busy, and that it will also be energized whenever the sender itself is busy, whether the relay equipments are all busy or not. Relay 112, associated with the group of relay equipments controlled by sender N^2 , is energized in a similar manner, a little more of the circuit being shown because relay equipment M^2 is the second in the group rather than the first. Relay 113 (circuits not shown) is energized responsive to busy conditions in the third group in the same manner. There is a similar relay associated with each of the other groups of relay equipments to which the secondary switches have access, and in the present embodiment of the invention comprising six operators' senders (see Fig. 2) there will be three more relays arranged like the ones shown, the circuit through these omitted relays being indicated by the dotted conductor. It will be seen now that when none of the groups of relay equipments are in condition to receive a call, each group being busy either by reason of the fact that all the relay equipments themselves are busy or because the associated sender is in use, then all the relays 111, 112, etc., will be energized and a circuit will be established for relay 114. Relay 114, upon energizing, disconnects ground from the common conductor 109. If we assume now that a secondary switch, the switch S^5 for example, is seized in the process of extending a connection from the No. 1 office, when relay 107 is energized over the trunk conductors it will be unable to close the energizing circuit of relay 108, the secondary switch being thereby prevented from rotating in search of an idle trunk. This is done because rotation would be useless, there being in fact no trunks idle at this time. While the call is being held up in this way the A operator is advised of its temporary suspension by the continued presence on the line of the tone or signal produced by the signalling equipment Q , which may be similar to the usual busy signalling equipment, but which produces preferably a different characteristic signal. The operator will ordinarily wait on the line, as it

will rarely occur that the condition will endure for long; and as soon as some group of relay equipments at the No. 3 exchange becomes accessible ground will be restored 5 to conductor 109 and the switch S^5 will operate as usual.

It has been described how the test contacts of the relay equipments in each position are normally tied together by means of 10 the common conductors 171' etc., and the common conductor 201. This arrangement is designed to and ordinarily does render the entire position busy while the operator is engaged in setting up a call and any sender 15 busy while it is transmitting impulses thereafter, the the position may then be accessible via trunks associated with other senders.

Nevertheless, it does happen at comparatively 20 rare intervals that two calls will come in at the same time at the same position, generally being due to two secondary switches being seized at exactly the same instant, or it may be due to defective busy 25 test circuits. Although as stated this trouble occurs so seldom that it could perhaps be neglected, yet under certain conditions it may be considered worth while to prevent its ill effects and I have devised means for 30 doing so. Suppose that calls come in to the relay equipments M' and M^6 simultaneously. Certain relays pull up in both relay equipments until finally relays 132 and 332 are 35 energized, followed by the energization of relays 202 and 302. Relay 202 disconnects ground from conductor 241 and hence from conductor 364 which is included in the energizing circuit of relay 332. It follows that 40 although relays 132 and 332 both operate at once or rather start to operate, the latter relay will immediately fall back so that only one call will be extended to the operator which is the call received at relay equipment M' , the other call being held up temporarily 45 while the operator is setting the sender N' . As soon as sender N' is started transmitting impulses relay 202 deenergizes thereby permitting relay 332 to operate and extend the delayed call to the operator; 50 meanwhile and until this occurs the A operator is given a busy signal from the busy signalling machine Q^2 . It will be seen that the normally grounded conductor 241 is 55 looped through contacts of relays 202 and 302, associated with senders N' and N^2 , respectively, so that the sender N' will have preference over the other senders whenever simultaneous calls are received at the position, and sender N^2 will have preference 60 over sender N^3 under similar circumstances. This takes care of calls received simultaneously at relay equipments associated with different senders. But suppose two calls are received simultaneously at relay equipments 65 controlled by the same sender. To take care

of this situation each of the conductors such as conductor 364 is looped through normally closed contacts of the several relays, such as relay 334, of the several relay equipments of the group. Fig. 6 shows this very clearly, 70 conductor 364 being looped through normally closed contacts of a relay in the 1st relay equipment which corresponds to relay 334, thence through normally closed contacts of relay 334, relay equipment M^6 , 75 thence through normally closed contacts of a relay in the third relay equipment which corresponds to relay 334, and thence through normally closed contacts (not shown) of similar relays in all the other relay equipments in the group, there being a branch taken off at each relay equipment for the purpose of operating the relays such as relays 332. Thus it will be seen that in the 80 case of calls received simultaneously at relay equipments of the same group, the call received at the relay equipment which is closest to the grounded end of conductor 364 (or similar conductor) will have the preference. 85

Another feature relates to the provision of means whereby an operator can restore a sender to normal and reset it in case she makes a mistake in registering a number. Suppose the operator is setting up a number 90 on sender N' and accidentally depresses a wrong digit key. To go ahead under these circumstances and operate the starting key would result in giving the calling party the wrong number. Instead therefore she will 95 actuate momentarily the release key (Fig. 9) thereby closing circuits for relays 205 and 209. Upon energizing, relay 205 locks itself to ground G^{18} and also closes a circuit for relay 204 which relay grounds conductors 164 and 165 in order to maintain the relay equipment, M' for example, in the status quo, so to speak, while the sender is running down or returning to normal. This operation is initiated by the energization 100 of relay 209, as has previously been described, and the automatic switches are prevented from operating by the opening of the impulse transmitting circuit at armature 223 of relay 205. When the sender has returned 105 to normal relay 205 will be unlocked (this will be clear if the function of slow acting relay 210 is recalled) and relay 204 will deenergize an instant later, restoring the circuits over conductors 164 and 165' to their 110 former condition. The operator is able to tell when the sender has completely restored by the extinguishing of lamp L^6 and she will then reset the sender correctly. 115

What I claim as my invention is: 120

1. In a telephone system, two manual offices an automatic office, inter-office trunk lines connecting said offices, A operators at each manual office for receiving and extending inter-office calls to the proper office, B opera- 125

5 tors at all offices for completing incoming inter-office calls, and suitable connecting apparatus and circuits therefor associated with the said inter-office trunk lines whereby the A operators select the particular trunks to be used in extending inter-office calls and repeat the called numbers to the B operators over the selected trunks in identically the same manner whether the calls are being 10 extended to the other manual office or to the automatic office.

15 2. In a telephone system, two offices or exchanges provided with manual connecting apparatus, for connecting subscribers' lines, a third office provided with automatic switches for connecting subscribers' lines, inter-office trunk lines connecting said offices, A operators at each manual office for receiving and extending inter-office calls to 20 the proper office, B operators at all of said offices for completing inter office calls, such calls being completed at the said third office by means of automatic switches, other automatic switches at the manual offices, and 25 suitable connecting apparatus and circuits therefor associated with said inter-office trunk lines whereby the A operators in extending inter-office calls control said last mentioned switches to select trunk lines to the proper offices and perform the same routine operations whether calls are being extended to the other manual office or to the said automatic office.

30 3. In a telephone system, an A board divided into sections, each comprising a plurality of positions, a separate outgoing trunk multiple for each section, a separate group of trunking switches for each multiple, and a plurality of inter-office trunk lines accessible to all of said switches in common.

35 4. In a telephone system, an A board divided into sections, each comprising a plurality of positions, groups of automatic trunking switches, a separate outgoing trunk multiple extending from each section and terminating in a plurality of said groups of switches, groups of inter-office trunk lines accessible, respectively, to the said group 40 of switches in which one of said multiples terminates, and multiple connections whereby the groups of switches forming terminals of said other multiples are given access to said groups of trunk lines also.

45 5. In a telephone system, two switch board sections each comprising a plurality of A operator's positions, a group of trunk lines multiplied throughout the first section and divided into sub-groups, each sub-group 50 having an associated group of primary switches in which the trunk lines thereof terminate, another group of trunk lines multiplied throughout the other of said sections, and also divided into sub-groups, the trunk lines of each sub-group also terminating in 55 an associated group of primary switches, a plurality of groups of inter-office trunk lines, there being a group of said inter-office

an associated group of primary switches, a plurality of groups of inter-office trunk lines, there being a group of said inter-office trunk lines accessible to the primary switches of each sub-group multiplied in the first section, and multiple branches of said groups of inter-office trunk lines accessible to said groups of primary switches of the sub-groups multiplied in the second section. 70

6. In a telephone system, a plurality of trunk lines connected to multiple jacks in a plurality of A operator's positions, a group of automatic trunking switches in which said trunk lines terminate, a second plurality of trunk lines connected to multiple jacks in a different plurality of A operator's positions, a second group of automatic trunking switches in which said second group of trunk lines terminate, a third plurality of trunk lines accessible to switches in both of said groups and terminating in a third group of autotrunking switches, a plurality of B operator's positions and a plurality of cord circuits at each position, and suitable connections whereby each switch in said third group is given access to cord circuits in all of said B positions. 80

7. In a telephone system, two switch board sections each comprising a plurality of A operator's positions, a group of trunk lines multiplied throughout the first section and divided into sub-groups, each sub-group having an associated group of primary switches in which the trunk lines thereof terminate, another group of trunk lines multiplied throughout the other of said sections, and also divided into sub-groups, the trunk lines of each sub-group also terminating in an associated group of primary switches, a plurality of groups of inter-office trunk lines, there being a group of said inter-office trunk lines accessible to the primary switches of each sub-group multiplied in the first section, multiple branches of said groups of inter-office trunk lines accessible to said groups of primary switches of the sub-groups multiplied in the second section, a plurality of B operator's cord circuits, and a plurality of secondary switches for extending said inter-office trunk lines into connection with said cord circuits. 100

8. In a telephone system, two switch board sections each comprising a plurality of A operator's positions, a group of trunk lines multiplied throughout the first section and divided into sub-groups each sub-group having an associated group of primary switches in which the trunk lines thereof terminate, another group of trunk lines multiplied throughout the other of said sections, and also divided into sub-groups, the trunk lines of each sub-group also terminating in an associated group of primary switches, a plurality of groups of inter-office trunk lines, there being a group of said inter-office

- trunk lines accessible to the primary switches of each sub-group multiplied in the first section, multiple branches of said groups of inter-office trunk lines accessible 5 to said groups of primary switches of the sub-groups multiplied in the second section, a plurality of B operator's positions and a plurality of cord circuits at each position, a plurality of secondary switches in which 10 the said inter-office trunk lines terminate, and suitable connections whereby each secondary switch is given access to a cord circuit in all of said positions.
9. In a telephone system, automatic 15 trunking switches, a plurality of trunk lines extending to an operator's switchboard and accessible to said switches, means at said switchboard for dividing said trunk lines into groups and means for making the trunk 20 lines in all of said groups busy whenever a trunk line in one of said groups is seized by one of said switches.
10. In a telephone system, automatic 25 trunking switches, a plurality of groups of trunk lines accessible to said switches, means including automatic selector switches and an individual switch controller for each of said groups of trunks for extending calls there-over, and means for making the trunk lines 30 in all of said groups busy whenever a trunk line in one of said groups is seized by one of said switches.
11. In a telephone system, a plurality of 35 groups of trunk lines each terminating in a directly controllable selector switch, a plurality of operators' sending mechanisms there being a separate sender for controlling the selectors associated with the trunk lines of each group, trunking switches for ex-tending incoming calls to trunk lines in 40 said groups, and means for making the trunk lines in all of said groups busy whenever a trunk line in one of said groups is seized by one of said switches.
12. In a telephone system, automatic 45 trunking switches, a plurality of groups of trunk lines accessible to said switches, means for establishing connections over said trunk lines comprising selector and connector 50 switches and an impulse sender individual to each of said groups, means for adjusting said senders, and means for making all of said trunk lines busy whenever one of said senders is being adjusted.
13. In a telephone system, automatic 55 trunking switches, a plurality of groups of trunk lines accessible to said switches means for establishing connections over said trunk lines comprising selector and connector 60 switches and an impulse sender individual to each of said groups, a common setting de-vice for adjusting said senders, and means for making all the trunk lines of a group busy whenever any trunk line of such group 65 is seized by one of said trunking switches.
14. In a telephone system, automatic trunking switches, a plurality of groups of trunk lines accessible to said switches, means for establishing connections over said trunk lines comprising selector and connector 70 switches and an impulse sender individual to each of said groups, a common setting device for adjusting said senders, means for making all the trunk lines of a group busy whenever any trunk line of such group is seized by one of said trunking switches, and means for making all of said trunk lines busy while the said setting device is being operated.
15. In a telephone system, automatic 80 trunking switches, a plurality of groups of trunk lines accessible to said switches, means for establishing connections over said trunk lines comprising selector and connector switches and an impulse sender individual 85 to each of said groups, means for adjusting said senders, means for making all of said trunk lines busy whenever one of said senders is being adjusted, and means for re-moving the busy condition from all of said trunks while a sender is operating to estab-lish a connection except the trunks of the group associated with the operating sender.
16. In a telephone system, automatic 90 trunking switches, a plurality of groups of trunk lines accessible to said switches, means for establishing connections over said 95 trunk lines comprising selector and connector switches and an impulse sender individual to each of said groups, means for adjusting said senders, means for making all of said trunk lines busy whenever one of said senders is being adjusted, means for removing the busy condition from all of said trunks while a sender is operating to 100 establish a connection except the trunks of the group associated with the operating sender, and means for removing the busy condition from the trunk of said last men-tioned group except the trunk line in use 105 when the sender has completed its operation.
17. In a telephone system, a plurality of trunk lines divided and sub-divided into main groups and sub-groups, each trunk line terminating in an automatic trunking 110 switch, a plurality of impulse sending mech-anisms there being a separate sender asso-ciated with the trunk lines of each sub-group, a lesser plurality of operator's key sets, each key set being adapted to control 115 the senders associated with the sub-groups of a particular main group, a plurality of autoswitches for extending calling lines into connection with said trunk lines, each switch having access to one or more trunk lines in each of said main groups, and means responsive to the seizure of any trunk line for making the remaining trunk lines in the sub-group busy.
18. In a telephone system a plurality of 120

group associated with the operating sender.

24. In a telephone system, a plurality of trunk lines divided and sub-divided into main groups and sub-groups, each trunk line terminating in an automatic trunking switch, a plurality of impulse sending mechanisms there being a separate sender associated with the trunk lines of each sub-group, a lesser plurality of operator's key sets, each key set being adapted to control the senders associated with the sub-groups of a particular main group, automatic trunking switches for extending calling lines into connection with said trunk lines, and busy means associated with each of said senders for rendering all the trunks in its associated group busy whenever one of said trunks is seized.
25. In a telephone system, a plurality of trunk lines divided and sub-divided into main groups and sub-groups, each trunk line terminating in an automatic trunking switch, a plurality of impulse sending mechanisms there being a separate sender associated with the trunk lines of each sub-group, a lesser plurality of operator's key sets, each key set being adapted to control the senders associated with the sub-groups of a particular main group, automatic trunking switches for extending calling lines into connection with said trunk lines, and busy means associated with each of said senders for rendering all the trunks in its associated group busy whenever one of said trunks is seized.
26. In a telephone system, a plurality of trunk lines divided and sub-divided into main groups and sub-groups, each trunk line terminating in an automatic trunking switch, a plurality of impulse sending mechanisms there being a separate sender associated with the trunk lines of each sub-group, a lesser plurality of operator's key sets, each key set being adapted to control the senders associated with the sub-groups of a particular main group, automatic trunking switches for extending calling lines into connection with said trunk lines, and means responsive to the seizure of a trunk line in any main group for making the remainder of the trunk lines in such group busy.
27. In a telephone system, a plurality of trunk lines divided and sub-divided into main groups and sub-groups, each trunk line terminating in an automatic trunking switch, a plurality of impulse sending mechanisms there being a separate sender associated with the trunk lines of each sub-group, a lesser plurality of operator's key sets, each key set being adapted to control the senders associated with the sub-groups of a particular main group, automatic trunking switches for extending calling lines into connection with said trunk lines, and means responsive to the seizure of any trunk line for making the remaining trunk lines in the sub-group busy.
28. In a telephone system, a plurality of trunk lines divided and sub-divided into main groups and sub-groups, each trunk line terminating in an automatic trunking switch, a plurality of impulse sending mechanisms there being a separate sender associated with the trunk lines of each sub-group, a lesser plurality of operator's key sets, each key set being adapted to control the senders associated with the sub-groups of a particular main group, automatic trunking switches for extending calling lines into connection with said trunk lines, and busy means associated with each of said senders for rendering all the trunks of the main group busy while the key set is busy in setting one of its associated senders.
29. In a telephone system, a plurality of trunk lines divided and sub-divided into main groups and sub-groups, each trunk line terminating in an automatic trunking switch, a plurality of impulse sending mechanisms there being a separate sender associated with the trunk lines of each sub-group, a lesser plurality of operator's key sets, each key set being adapted to control the senders associated with the sub-groups of a particular main group, automatic trunking switches for extending calling lines into connection with said trunk lines, and busy means associated with each of said senders for rendering all the trunks in its associated group busy whenever one of said trunks is seized, and busy means associated with each operator's key set for rendering all the trunks of the main group busy while the key set is busy in setting one of its associated senders.
30. In a telephone system, a plurality of trunk lines divided and sub-divided into main groups and sub-groups, each trunk line terminating in an automatic switch, separate switch controllers individual to each sub-group, operator's equipment individual to each main group, automatic trunking switches for extending calling lines into connection with said trunk lines, and busy connections in each sub-group whereby all the trunks thereof are made busy whenever any one of them is seized.
31. In a telephone system, a plurality of

- trunk lines divided and sub-divided into main groups and sub-groups, each trunk line terminating in an automatic switch, separate switch controllers individual to each sub-group, operator's equipment individual to each main group, automatic trunking switches for extending calling lines into connection with said trunk lines, busy connections in each sub-group whereby all the trunks thereof are made busy whenever any one of them is seized, and busy connections for each main group for rendering all the sub-groups busy whenever any one sub-group becomes busy.
- 5 32. In a telephone system, a plurality of trunk lines divided and sub-divided into main groups and sub-groups, each trunk line terminating in an automatic switch, separate switch controllers individual to each sub-group, operators controlling apparatus common to said controllers and individual to each main group, automatic trunking switches for extending calling lines into connection with said trunk lines, and busy connections in each sub-group for rendering all the trunks thereof busy whenever the associated controller is in use.
- 10 33. In a telephone system, a plurality of trunk lines divided and sub-divided into main groups and sub-groups, each trunk line terminating in an automatic switch, separate switch controllers individual to each sub-group, operator's controlling apparatus common to said controllers and individual to each main group, automatic trunking switches for extending calling lines into connection with said trunk lines, busy connections in each sub-group for rendering all the trunks thereof busy whenever the associated controller is in use, and busy connections in each main group for rendering all its sub-groups busy whenever the associated operator's controlling apparatus is in use.
- 15 34. In a telephone system, a plurality of trunk lines divided and sub-divided into main groups and sub-groups, each trunk line terminating in an automatic switch, separate switch controllers individual to each sub-group, operator's controlling apparatus common to said controllers and individual to each main group, automatic trunking switches for extending calling lines into connection with said trunk lines, and circuit connections such that whenever a trunk line is seized by one of said trunking switches, the other trunk lines of the same sub-group and also the trunk lines of the other sub-groups of the same main group are made busy.
- 20 35. In a telephone system, a series of trunk lines, said trunk lines divided into two groups, a first group and a second group, operator's equipment associated with the first group of trunks, a series of automatic switches associated with the first group of trunks, one switch for each trunk in said first group; operator's equipment associated with the trunk lines of the second group, automatic trunking switches associated with the second series of trunks, one automatic switch for each trunk, the trunks of the first group divided into sub-groups and the trunks of the second group divided into sub-groups; an impulse sending equipment for the operator of the first group, an impulse sending equipment for the operator of the second group, the impulse sending equipment in the first group having an impulse sender for each sub-group of the first group and the impulse sending equipment of the second group having an impulse sender for each sub-group of the second group; a common operator's key set in each group for controlling the impulse senders of the group, a plurality of automatic switches for extending the calling lines into connection with said trunk lines and into connection with the operator's equipment in either group, each switch having access to one or more trunk lines in each of said main groups, said trunk lines and operator's equipment including means responsive to the seizure of one of said trunk lines in a main group for making the remainder of the trunk lines in such main group busy, and for extending a talking connection through the operator's equipment of said last mentioned main group to the operator thereof, whereby the operator may ascertain the number of the subscriber with whom connection is desired, the key set of the responding operator who receives the call having means whereby when the key is operated in accordance with the digits of the called number, for controlling one of the impulse senders associated therewith to set the same in accordance with the desired number and for removing the busy condition from the main group as a whole while retaining the sub-group to which the impulse sender belongs busy as a whole, and means in said impulse sender for removing such busy potential from the said sub-group as a whole when the call has been completed and for retaining the busy potential over the individual trunk of the sub-group over which the impulse sender has extended the connection.
- 25 36. In a telephone system, trunk lines extending by way of an operator's position to automatic switches, a plurality of sending devices each for controlling connections over a different plurality of said trunk lines, a common setting device, and means responsive to the seizure of any trunk line for connecting said setting device in operative relation to the proper sender.
- 30 37. In a telephone system, a plurality of trunk lines accessible to calling lines, automatic switches for extending said trunk

- lines to desired called lines, a plurality of controllers each adapted to control a plurality of said switches to establish a complete connection over one of said trunk lines, 5 and an operator controlled setting device comprising only ten keys, each of said keys being common to said controllers. 38. In a telephone system, incoming trunk lines terminating in automatic trunking switches, groups of local trunk lines accessible to said switches and extending through operator's positions to corresponding groups of automatic selector switches, there being a plurality of said groups extending through 10 each of said positions, an impulse sender individual to each group of local trunk lines for controlling connections thereover, and a common setting device at each operator's positions for adjusting the impulse senders 15 associated therewith. 39. In a telephone system, means for connecting calling and called lines including trunk lines and sets of serially related automatic switches, a plurality of controllers 20 each adapted to operate a set of said switches to establish a complete connection over one of said trunk lines, and a single operator's key set for adjusting said plurality of controllers, each key of the set being adjustable to control the movement of any one of said switches. 40. In a telephone system, a plurality of trunk lines divided into main groups and sub-groups, each trunk line terminating in 25 an automatic trunking switch, a plurality of impulses sending mechanisms there being a separate sender associated with the trunk lines of each sub-group, and a lesser plurality of operator's key sets, each key set being 30 adapted to control the senders associated with the sub-groups of a particular main group. 41. In a telephone system, a plurality of groups of trunk lines, a plurality of non-numerical automatic trunking switches for extending calling lines to idle trunk lines in 35 said groups, a control relay in each switch for closing the stepping circuit, a line relay in each switch for closing the circuit of the associated control relay, a relay actuated whenever all of said trunk lines are busy for 40 opening the circuits of said control relays, thereby preventing the selective operation of any one of said switches by which it is 45 attempted to select and connect with one of said trunk lines, and means for giving a 50 busy signal to the calling party. 42. In a telephone system, a plurality of groups of trunk lines, means for connecting 55 calling and called telephone lines over said trunk lines comprising non-numerical automatic trunking switches, each switch having access by a single selective movement to one or more trunk lines in each of said groups, and means for holding a call in suspense and for preventing further extension thereof after it has reached one of said switches provided all of said trunk lines are busy, said holding means comprising individual trunk relays, group relays controlled by the individual relays, and a relay common to 60 said switches under the joint control of said group relays. 43. In a telephone system, a plurality of groups of trunk lines, means for connecting calling and called telephone lines over said trunk lines comprising automatic trunking switches, each switch having access by a single selective movement to one or more trunk lines in each of said groups, and means for holding a call in suspense and for preventing further extension thereof after it has reached one of said switches provided all of said trunk lines are busy, operators controlling the establishment of connections, and means for giving the operator controlling the connection a busy signal. 44. In a telephone system, means for connecting a calling and called line comprising a non-numerical rotary automatic switch and a plurality of trunk lines accessible thereto, means effective during the establishment of a connection for preventing the rotation of said switch in search of an idle trunk line and for holding the call in suspense in case all of said trunk lines are busy, an operator controlling the connection, and means for giving the operator a signal while the call is suspended. 45. In a telephone system, means for connecting calling and called lines comprising groups of trunk lines and a plurality of automatic switches, operator's equipment for controlling the establishment of connections adapted for connection with any trunk line when it is in use by a calling line, busy test circuits for preventing the connection of two calling lines with trunk lines in the same group at the same time, and means whereby upon the failure of said busy test circuits to prevent such simultaneous connections one of the calls is held in suspense and the said operator's equipment is connected to the several connected trunks in succession to control the connections thereover. 46. In a telephone system, means for connecting calling and called lines comprising a plurality of serially related automatic switches, an operator's impulse sender for operating said switches, said sender being adapted to be set in accordance with the number of a called line and being adapted to perform automatically thereafter a complete cycle of operations whereby said switches are successively actuated to complete the connection, operator controlled means for setting said sender, and means whereby in case the operator makes a mistake in the

setting the call may be held in suspense and the sender permitted to complete its cycle of operations without actuating said switches.

47. In a telephone system, an A board and a B board, an outgoing trunk multiple at said A board, cord circuits at the B board, primary and secondary trunking switches and interconnecting trunk lines for connecting jacks in said multiple with said cord circuits, a relay for each of said trunk lines energized when the same is busy, and means whereby when all of said relays are energized all the jacks in said multiple are made busy.

48. In a telephone system, a B operator's cord circuit for completing inter-office connections, a lamp signal at said cord circuit, means for flashing said lamp signal when a call is received, means for stopping the flashing of said signal as soon as the connection is completed, and means for thereafter operating said lamp signal to give a steady light when the conversation is finished and disconnection is desired.

49. In a telephone system comprising A and B operators' positions, inter-office trunk lines accessible to the A operators, link circuits for use by the B operators in completing connections, means for placing a distinctive audible tone signal on one of said trunk lines when it is taken for use by an A operator, an automatic trunking switch for thereafter extending said trunk line to an idle one of said link circuits, and means for then disconnecting the said tone signal to notify the A operator that the connection to the link circuit has been completed.

50. In a telephone system, means including groups of trunk lines for connecting calling and called lines, operator's equipment for controlling the establishment of a connection from any trunk line when it is in use by a calling line, means for preventing the connection of two or more calling lines with trunk lines in the same group at the same time, and means whereby upon the failure of said second means to prevent such simultaneous connections all of the calls except one are held in suspense and the said operator's equipment is connected to the several connected trunks in succession to control the connections therefrom.

51. In a telephone system, a plurality of serially related automatic switches, an operator's impulse sender for operating said switches, said sender being adapted to be set in accordance with the number of a called line and being adapted to perform a complete cycle of operation thereafter

whereby said switches are successively actuated to complete the connection, operator controlled means for setting said sender and for starting its operation, and means under the control of the operator for preventing the operation of said sender from affecting said switches should the wrong number have been set up.

52. In a telephone system, an operator's cord circuit for completing inter-office connections, a signal at said cord circuit, means for operating said signal when a call is received, means for disconnecting said signal as soon as the connection is completed, and means for thereafter operating said signal in a distinctly different manner when the conversation is finished and disconnection is desired.

53. In a telephone system, an A board and a B board, an outgoing trunk multiple at said A board, cord circuits at the B board, primary and secondary trunking switches and interconnecting trunk lines for connecting jacks in said multiple with said cord circuits, means individual to each trunk line for making the same busy when taken for use, and means operated when all of said trunk lines are taken whereby all of said jacks are made busy.

54. In a telephone system, an A board and a B board, an outgoing trunk multiple at said A board, cord circuits at the B board, primary and secondary trunking switches and interconnecting trunk lines for connecting jacks in said multiple with said cord circuits, means individual to each trunk line for making the same busy when taken for use, and means operated in response to the joint operation of all of said individual means whereby all of said jacks are made busy.

55. In a telephone system comprising A and B operators' positions, inter-office trunk lines accessible to the A operators, link circuits for use by the B operators in completing connections, a distinctive audible tone signalling machine normally disconnected from said lines, means for connecting said machine to one of said lines when it is taken for use by an A operator, an automatic trunking switch for thereafter extending the trunk line in use to an idle one of said link circuits, and means for then disconnecting the said machine to notify the A operator that the connection to the link circuit has been completed.

Signed by me at Chicago, Cook county, State of Illinois, this 12th day of Nov., 1919.

JOHN WICKS.
